UNITED STATES PATENT OFFICE

EDWARD S. BLACK, OF CHICAGO, ILLINOIS, ASSIGNOR TO PETTIBONE MULLIKEN COMPANY, A CORPORATION OF DELAWARE

DIPPER CONSTRUCTION

Application filed August 25, 1932. Serial No. 630,466.

The invention relates to dippers, or buckets, of the type shown and described in my co-pending application, Serial No. 618,389, filed June 20, 1932, dippers or buckets of this type being used in excavating or similar work.

The primary object of the invention is to provide improved front construction for a fabricated dipper or bucket of the character described.

Another object is to provide a dipper or bucket in which portions of the front construction may be assembled or dis-assembled with comparative ease and, preferably, without inserting or removing rivets or other relatively permanent fastening devices.

Other objects and advantages will become apparent as the following detailed description progresses, reference being had to the accompanying drawings, wherein—

Figure 1 is a view in side elevation of a dipper or bucket which embodies the invention.

Figure 2 is a fragmentary face view of the dipper front.

Figure 3 is a view looking at the left hand end of the improved dipper as it is viewed in Figure 1, Figure 3 being partly in section to illustrate certain details of construction, and

Figure 4 is an enlarged fragmentary section taken on line 4—4 of Figure 3.

Referring to the drawings wherein a preferred embodiment of the invention is illustrated, the reference character 5 designates generally the body portion of the improved dipper, which body portion may be of any suitable or preferred construction. The side walls of the body portion 5 are designated by the reference character 6 and terminate short of the front or digging wall of the dipper.

In the particular construction illustrated, the improved dipper front comprises a main body section 13 and an upper lip section 14 which is interlocked with the body section 13 and provides seats for a plurality of dipper teeth 15. Intermediate the seats for the dipper teeth 15, the upper lip section 14 is provided with cutting edge portions 16.

The body section 13 and the upper lip section 14 constitute the improved dipper front,

in this instance, and are of general trough shape as shown in Figure 3, the main body section 13 having rearwardly extending side plates or wings 12 which are secured to the side walls 6 by rivets 7, or the equivalent. The upper lip section 14 is provided with rearwardly extending wings or side plates 14b, the side plates 14b being formed integral with the front wall 14a of the upper lip section 14.

A rib 17 preferably formed integral with the main body section 13 is provided with an upwardly extending flange 20. The rib 17 and the flange 20 extend continuously across the front surface of the main body section 13 and, in this instance, a little more than half way across the side plates 12 of the body section 13. (See Figures 1 and 3).

The upper edge of the body section 13 is provided with an upwardly extending flange 21 offset forwardly from the rear face 22 of the body section.

The flange 21 extends across the entire front surface of the body section 13 and more than half way back along the outer surfaces 75 of the side plates 12.

The outer or front surface of the body section 13 is provided, between the rib 17 and the flange 21, with a series of spaced, substantially parallel ribs 23 which extend lengthwise of the dipper front, these ribs being shown as extending at their outer faces, designated as 24, substantially flush with the outer face of the flange 21, but short of the rear surface of the flange 20.

The lip section 14 and the body section 13 are preferably provided as castings. The lip section 14 is formed of a cored body portion 26 which extends along the upper edge portion of the body section 13 and around the sides thereof as shown (Figures 3 and 4), the body portion 26 being provided with an integral skirt portion 28 which terminates at its lower edge in a depending rearwardly offset flange 29 adapted to enter the space between the flange 20 and the outer surface of the body section 13. (See Figure 4).

The body portion 26 is provided at its rear edge with a depending flange 30 adapted to hook over the flange 21 on the body section 13.

and interlocked therewith as shown, the rear face 31 of the flange 30 being substantially flush with the rear or inner surface 22 of the body section 13. It will be noted that the inner or rear surface of the skirt 28 abuts 5 against the surfaces 24 of the ribs 23 with which the body section 13 is provided.

The body portion 26 of the lip section 14 is provided with spaced toothed bases 33 formed integral therewith. The bases 33 are cored out as represented at 34 and present, at their outer ends, sockets 35 to receive the shanks 36 of the teeth 15.

The lip section 14 is assembled with the body section 13 as illustrated in the drawings 15 so that the flange 30 interlocks with the flange 21 and the flange 29 extends, preferably, by a relatively close fit, into the space between the flange 20 and the outer or front 20 surface of the body section 13.

The sections 13 and 14 are secured, preferably, to each other as by means of bolts 44 which pass through the ribs 23 and the front wall 14a of the section 14. The bolts 44 prevent longitudinal displacement of the sections 13 and 14 relative to each other.

It will be noted that the flanges 20, 29, 21 and 30 extend from one lateral edge of the upper lip section 14 to the opposite lateral 30 edge thereof. These lateral edges are identified by the reference character 14c. At the upper ends of the lateral edges 14c, lugs 14d formed integral with the upper section 14 project into notches 13d provided in the lower section 13. (See Figures 1 and 3.)

It will be readily understood that the improved construction possesses a high degree of strength and is relatively light in weight. It will also be understood that the improved 40 construction provides for the ready substitution of a new lip section for a worn one and that, when bolts 44 are employed to secure the sections to each other, it is not necessary to remove rivets or other relatively permanent 45 fastening devices before the lip section may be dis-assembled from the lower section 13.

While I have illustrated and described certain constructions constituting embodiments of my invention, I do not wish to be understood as intending to limit my invention thereto, as the constructions shown may be variously modified and altered and the invention embodied in other forms of structure without departing from the spirit of my 55 invention.

What I regard as new, and desire to secure by Letters Patent, is:

1. A front section of a dipper comprising a body section, and a separate upper section, 60 said sections having a plurality of sets of interlocking flanges extending substantially from one lateral edge of said upper section to the opposite lateral edge thereof.

2. A front construction of a dipper comprising a body section and a separate upper

section, said body section being provided below its upper edge with an upwardly extending projection and said upper section lapping a rearwardly facing surface of said body section at the upper edge of the latter and also lapping the rear surface of said projection, 70 said projection extending substantially from one lateral edge of said upper section to the opposite lateral edge thereof.

3. A front construction of a dipper comprising a body section and a separate upper section, said body section having an upwardly extending projection adjacent its upper edge and offset toward the front side of said body section and provided below its upper edge with an upwardly extending projection, 75 said upper section lapping the rear surfaces of said projections, said projections extending substantially from one lateral edge of said upper section to the opposite lateral 80 edge thereof.

4. A front section of a dipper comprising a body section, and a separate upper section, 90 said sections having a plurality of sets of interlocking projections located at different elevations and extending substantially from one lateral edge of said upper section to the opposite lateral edge thereof.

5. A front section of a dipper comprising a trough-shaped body section, and a separate trough-shaped upper section, said sections having a plurality of sets of interlocking projections located at different elevations and extending substantially from one lateral edge 95 of said upper section to the opposite lateral edge thereof.

6. A front construction of a dipper comprising a body section, and a separate upper section, said upper section having a portion which laps a rearwardly facing portion of 105 said body section and extends substantially from one lateral edge of said upper section to the opposite lateral edge thereof, said upper section having a portion extending opposite said first-referred-to portion at the front side of said body section depending to a point below the lower edge of said first-referred-to portion and extending continuously across the front face of said body portion.

7. A front construction of a dipper comprising a body section, a separate upper section, said upper section having a portion which laps a rearwardly facing portion of 110 said body section and extends substantially from one lateral edge of said upper section to the opposite lateral edge thereof, said upper section having a portion extending opposite said first-referred-to portion at the front side of said body section depending to a point below the lower edge of said first-referred-to portion and extending continuously across the front face of said body portion, 115 and means extending through said last-referred-to portion of said upper section and 120

125

said body section for securing the upper section in place.

8. A front construction of a dipper comprising a trough-shaped body section, a separate upper trough-shaped section, said upper section having a portion lapping a rearwardly facing surface of said body section and extending upwardly therebeyond, and means for preventing deflection of end portions of said upper section comprising grooves in one of said sections into which portions of the other of said sections extend, said grooves opening in the direction of the planes of the side walls of said body section.

15 9. A front construction of a dipper comprising a trough-shaped body section, a separate upper trough-shaped section, said upper section having a portion lapping a rearwardly facing surface of said body section and extending upwardly therebeyond and substantially from one lateral edge of said upper section to the opposite lateral edge thereof, and means for preventing deflection of end portions of said upper section comprising grooves in one of said sections into which portions of the other of said sections extend, said grooves opening in the direction of the planes of the side walls of said body section.

20 10. A front section of a dipper comprising a body section, a separate upper section, said sections having a plurality of sets of interlocking projections located at different elevations and extending substantially from one lateral edge of said upper section to the opposite lateral edge thereof, said upper section extending above said sets of projections, and means for preventing deflection of the ends of said upper section at its upper portion in either of opposite directions comprising interlocking portions formed of parts of said sections.

25 11. A front construction of a dipper comprising a trough-shaped body section, a separate upper trough-shaped section, said sections having a plurality of sets of interlocking projections located at different elevations and extending substantially from one lateral edge of said upper section to the opposite lateral edge thereof, said upper section extending above said sets of projections, and means for preventing deflection of the ends of said upper section at its upper portion in either of opposite directions comprising grooves in one of said sections into which portions of the other of said sections extend, said grooves opening in the direction of the planes of the side walls of said body portion.

30 12. A front section of a dipper comprising a trough-shaped body section, and a separate trough-shaped upper section, said sections having a plurality of sets of interlocking flanges extending substantially from one lateral edge of said upper section to the opposite lateral edge thereof.

35 13. A front construction of a dipper com-

prising a body section and a separate upper section, said body section being provided below its upper edge with an upwardly extending projection and said upper section lapping a rearwardly facing surface of said body section at the upper edge of the latter and also lapping the rear surface of said projection, said projection and the portion of said upper section lapping the rearwardly facing surface of said body section extending substantially from one lateral edge of said upper section to the opposite lateral edge thereof.

40 14. A front construction of a dipper comprising a trough-shaped body section and a separate trough-shaped upper section, said body section having an upwardly extending projection adjacent its upper edge and offset toward the front side of said body section and provided below its upper edge with an upwardly extending projection, said upper section lapping the rear surfaces of said projections, said projections extending substantially from one lateral edge of said upper section to the opposite lateral edge thereof.

45 In witness whereof, I have hereunto subscribed my name this 18th day of August, 1932.

EDWARD S. BLACK.
